WATER-HEATING SYSTEM

Martin A. Thomas, Abilene, Tex., assignor of one-third to Wayland D. Keith, Wichita Falls, Tex.

Application July 11, 1944, Serial No. 544,431

14 Claims. (Cl. 236—20)

1

This invention relates to improvements in water heating systems, and particularly to water heating systems utilizing thermal control for the heating media, as, for instance, turning on the gas, or other source of heat, when the water has cooled to a predetermined temperature.

The storage-type water heater is the most widely used at the present time, but this type of system can be improved materially as to efficiency and lower cost of operation, while yet maintaining all advantages of this system as well as of an instantaneous system.

Various thermal controlled water heating systems have been proposed heretofore, but for the most part, these have been inadequate, as the lag between the time when the water is turned on and the time that fuel ignites at the burner is so long that an accumulated amount of cold water has time to flow into the system before the burner starts operating.

An object of this invention is to provide a water heating system whereby the thermostatic control turns on the gas or other heating media almost simultaneously upon the withdrawal of hot water from the system.

Another object of this invention is to provide a water heating system which will maintain two different water temperatures for withdrawal and which are controlled by a single thermostat.

Another object of this invention is to provide a thermo-control valve to direct cold water into close proximity to the thermostat for accelerated actuation of the igniting of the fuel at the burner.

A still further object of this invention is to provide a water heating system utilizing a thermo-syphon circulation system between the heating tank and the storage tank, thereby eliminating the necessity of a mechanical circulating means.

Yet another object of this invention is to provide a valve which is pressure operated when the temperature reaches a predetermined degree.

Another object of this invention is to provide a coil within a flue of the water heating system to further heat the water.

The above and other objects and features of the invention will be apparent to those skilled in the art, from a consideration of the following detailed description taken in conjunction with the accompanying drawings, in which:

Fig. 1 is a side elevation of a preferred embodiment of the invention, with parts broken away and in section to illustrate details of construction;

Fig. 2 is a vertical section through a modified form of the invention, with parts broken away and in section to show details of construction;

Fig. 3 is an illustration of a still further modification of the invention, with parts broken away and in section to illustrate details of construction;

2

Fig. 4 is a side elevation of another modification of the invention with parts broken away and in section to illustrate the details of construction;

Fig. 5 is an enlarged longitudinal section of a thermal valve switching mechanism applied to a burner, with parts in elevation;

Fig. 6 is a cross-section through the storage tank, taken on the line 6—6 of Fig. 1; and

Fig. 7 is an enlarged longitudinal section of a pressure operated valve used in the system of Fig. 4.

With more detailed reference to Fig. 1 of the drawings, the numeral 1 designates a tank for heating water, which has a primary burner 2 and a secondary burner 2' in the combustion chamber 3 at the lower portion thereof. A vent or flue 4 is provided through the top of the tank 1 to pass off the products of combustion from the chamber 3.

The tank 1 is provided with a water inlet pipe 5 and an outlet pipe 6, which outlet pipe 6 is connected with one end of a hot water storage tank 7. A hot water supply pipe 8 is connected with the upper portion of the water storage tank 7 and leads therefrom. A return circulating pipe 9 leads downward from the lower portion of the storage tank 7 and interconnects through a check valve 10 with the inlet pipe 5.

A cold water supply pipe 11 is connected with one side of a diverter valve, generally designated at 12, and which is constructed as shown in Fig. 5. The diverter valve 12 has an inlet opening 13 connected with the pipe 11, and discharge openings 14 and 15. The opening 14 is connected with a pipe 14a, leading to a perforated tube 14b (Fig. 6) within the storage tank 7. The tube 14b has perforations at 14c therein. The discharge opening 15 is connected with the inlet pipe 5 through a pipe 15a (Fig. 1).

The valve 12 has a disc 16 secured to an axial plunger shaft 17. A disc 18 is adjustably secured on a threaded portion 19 of the plunger shaft 17. A nut 20 is used to secure disc 18 in adjusted position. These discs 16 and 18 are positioned within a chamber 21 of the valve 12 so as to seat alternately on valve seats 22 and 23, respectively. A sleeve portion 24 of the casing of the valve 12 carries the seat 23, and is removably attached to the valve body 12 so the seats and discs of the valve may be properly assembled or reconditioned. A spider 26 is formed within the sleeve portion 24 so as to guide the axial plunger shaft 17.

A brace 28 is secured in bridging relation to the opposite end of the casing of the valve 12 for attachment of a threaded tubular member 29. The tubular member 29 is screw-threaded through a plate 30, which plate 30 is attached to the wall of the tank 1 over an opening thereon at one side of the chamber 3. A lock nut

31 secures the tubular members 29 in a fixed position relative to the plate. On the end of the tubular member 29 inside the chamber 3 is secured a bi-metallic member 32 which is adjustably secured in place by nuts 33. Another section 34 of the bi-metallic member 32 is adjustably secured thereto by a clamp 35. The outer extremity of bi-metallic member 34 is secured to the axial plunger shaft 17 by nuts 36. The inner end of the tubular member 29 is held in spaced relation to burner 2' by a brace 37 which is adjustably mounted on the tubular member 29 by nuts 38.

A fuel supply pipe 39 is connected with the burners 2 and 2' and has a thermostatic control valve 40 therein, the thermostat of which is located in the hot water storage tank 7. A pilot light 41 is provided to ignite the burner 2.

In the operation of the system shown in Fig. 1, cold water enters the system through the supply pipe 11. With the diverter valve 12 in its normal position, as shown in Fig. 5, the valve 18 being open, a small supply of water is directed immediately through the pipe 14a to the perforated tube 14b (Fig. 6) from which it is directed outwardly through perforations 14c against the thermostat of the valve 40, forming a small localized cool water zone surrounding and cooling said thermostat. With the cool water zone located within the normally hot water zone, this cool water will gradually become heated to operate the thermostatically controlled fuel supply valve 40, but only after a sufficient time has elapsed to permit the heating of the cool water as it comes into the tank 1. The thermostat 40 is of the conventional type that opens a fuel valve when cooled, permitting fuel to flow to the burners 2 and 2'. The pilot light 41 burns in the chamber 3 so the burners 2 and 2' will be ignited when fuel is supplied thereto. The thermo-element 34 is preferably heated by a secondary burner 2', which burner 2' is connected in parallel with the primary burner 2, which burner 2 is used for heating the incoming and the recirculated water. Therefore, the secondary burner may be independently adjusted so as to give the correct amount of heat on the thermo-element irrespective of the heat at which the primary burner is adjusted to operate.

As soon as the heat from the burner 2' is supplied to the bi-metallic element 34, an expansion of this element takes place so as to move plunger shaft 17 (Fig. 5) to the left to close the valve 18 and open the valve 16. In so doing, the water will then be directed from the cold water supply pipe 11 through the valve 12 and outlet 15 to the pipe 15a, thence into inlet pipe 5 in the lower portion of tank 1 (Fig. 1), however, the cool water that is introduced around the thermo-element of valve 40 will gradually become warmed so as to continue to direct fuel to the burners 2 and 2' after the diverter valve 18 has seated on seat 23, to divert the cool water into the area immediately above the burners, thereby preventing any lag in the starting of the heating of the incoming water, as hot water is being withdrawn.

As this operation has been taking place, the burner 2 has been heating the water in the tank 1 and as additional cold water is introduced through the pipe 5 heating thereof is started immediately. Thus, as fast as the water is withdrawn through the hot water supply pipe 8 from the storage tank 7, more hot water is supplied to the storage tank 7 through the pipe 6 interconnecting the top of the tank 1 and the tank 7.

Upon ceasing to withdraw hot water from the hot water supply pipe 8, the system will have a tendency to equalize the temperature of the two tanks. The burners 2 and 2' will continue to burn and the water will circulate out of the top of the tank 1 through the pipe 6 into the storage tank 7, then out of the bottom of the storage tank 7, through the pipe 9, check valve 10, and pipe 5 back into the bottom of the tank 1. Therefore, with this circulation loop, water in the storage tank 7 is maintained at the desired temperature by the thermostatic valve 40. Inasmuch as the thermostat of the valve 40 is in close proximity to the water supply outlet 8, the water to be withdrawn can be maintained more nearly at the desired temperature than if the thermostat were located in the heater tank 1.

As the water in the storage tank 7 is heated to a predetermined temperature, according to the setting of the thermostatic valve 40, the latter will close off the supply of fuel to the burners 2 and 2', thereby permitting the bi-metallic thermal element 34 to cool, which will move the plunger 17 to close the valve 16 which will close the passage to the outlet 15. These parts will remain in this position until such time as the burners are again ignited. If it is desired, the valve 18 may be adjusted along the threaded portion 19 of axial plunger rod 17 so as to divert a small flow of water onto the thermostat of the valve 40 while the greater portion of the water is directed into the bottom of the tank 1. In this manner sufficient water can be directed onto the thermostat of the valve 40 to keep it cooled sufficiently to maintain the operation of the burners, but not supplying sufficient water to cool the water in the storage tank 7. The valve 16 may be adjusted with respect to the seat 22 by an adjustment of the plunger shaft 17 by the nuts 36, to allow a flow thereby in closed position.

The system, when used with the thermostat in the storage tank, will actuate the valve 12 to start the heating of the water in the heater tank immediately upon the withdrawal of hot water from the storage tank. Therefore, the capacity of the tanks may be less than would be required ordinarily, as the capacity output of hot water is much greater, since there is no time lag between the withdrawal of water from the storage tank and the time the thermostat 40 starts the heating of water in the heater tank, as is the case with conventional systems.

By the use of the system above described, instantaneous water heating is obtained without the use of coils, which are objectionable where mineral deposits, such as lime or the like are prevalent. This system makes possible the use of smaller capacity tanks than heretofore and still obtain the desired volume output of hot water, without the necessity for maintaining a large reserve of hot water, thereby effecting a material saving of fuel. The smaller capacity system also reduces the cost of initial installation, as well as lowering the cost of operation due to maintaining the desired temperature in a smaller quantity of water.

The form of the invention shown in Fig. 2 has a water tank 51 having burners 52 and 52' in a combustion chamber 53. A flue 54 extends upwardly through the tank to vent the products of combustion from the combustion chamber 53. The tank 51 is provided with a water inlet pipe 55 in the lower portion thereof.

A diverter valve 57, similar to the valve 12 shown in Fig. 5, as described above, is provided for controlling the supply of water from pipe 58 either to the pipe 55 or to a pipe 59 connected with a perforated tube 60, similar to the tube 14b shown in Fig. 6. A bi-metallic thermostatic unit 61 is attached to an axial plunger shaft 62 for operating the valve elements in the valve 57.

A heating coil 63 is disposed in the upper portion of the combustion chamber 53 and extends through the flue 54 in which it is suspended by a brace 64. The coil 63 is connected at one end with a pipe 65 which extends in the tank 51 to an upper portion thereof but is diametrically disposed from perforated tube 60. The coil 63 has a normal outlet into a pipe 66 connected therewith and with an outlet pipe 56 to supply hot water to the desired point. However, a bypass 67 interconnects the pipe 66 with a pipe 68 through a check valve 69, the pipe 68 opening into the top of the tank 51 so water may be circulated through coil 63 and back into tank 51. A valve 70 is provided between the pipes 68 and 56, which valve connecting these together, is normally closed to prevent water from flowing from the pipe 68 into the pipe 56, unless desired.

A drain valve 71 may be located in the lower portion of tank 51, if desired.

A fuel supply line 72 has a thermostatic valve 73 therein, for supplying gas or other fuel to the burners 52 and 52'. A pilot light burner 74 is provided for igniting the burner 52.

This form of the invention shown in Fig. 2 is similar in operation in many respects to that shown in Fig. 1, except that a single tank 51 is used for both heating and storage. This is particularly desirable in a residence or wherever a small amount of hot water is required. The water may be maintained at a relatively low storage temperature, as for example 80 degrees to 90 degrees F., which increases the useful life of the tank. The booster coil 63 has sufficient heat exchange surface to raise the water temperature from 80 or 90 degrees F. to 140 or 160 degrees F., as might be desired.

In this form, the water is admitted through the pipe 58 into the diverter valve 57 which may be of the same construction shown in Fig. 5. This valve 57 will direct water first through the pipe 59 and the perforated tube 60 onto the thermostatic element of the valve 73, which will cool the thermostat sufficiently to open the valve 73 and permit the fuel to pass through pipe 72 to the burners 52 and 52' which will be ignited by the pilot light 74. As soon as the burners are ignited, the bi-metallic unit 61 of the diverter valve 57 actuates the plunger shaft 62 so as to shift the valve elements therein and direct the water from the supply line 58 through the diverter valve 57 and the inlet pipe 55 into the lower portion of tank 51. In so doing the heat from burners 52 and 52' within the combustion chamber 53 will heat the lower portion of the water tank to cause an initial heating of the cold water.

As the hot water is withdrawn from the hot water supply pipe 56 the hotter water in the upper portion of tank 51 will be drawn through the pipe 65 into the coil 63 in the upper portion of the combustion chamber 53 and within the flue 54 where this water is further heated. The hot water will then pass outward from the coil 63 through the pipe 66 into the hot water supply pipe 56. The valve 70 normally will be

closed when the coil 63 is being utilized. After the hot water has ceased to be withdrawn a circulation within the tank 51 will continue through the coil 63, by-pass pipe 67, check valve 69, and back through the pipe 68 in the top of the tank 51. This will be continued until the temperatures of the water reaches the predetermined setting of thermostatic valve 73, when said valve 73 will close and discontinue the flow of fuel through the line 72 to burners 52 and 52'. Then the bi-metallic element 61 will cool so as to move the valve members into the initial positions, as shown in Fig. 5.

By having the coil 63 disposed within the combustion chamber 53, sweating or condensation of moisture on the coils is greatly reduced or completely eliminated, due to the fact that the water introduced into the coil has been heated initially and it is not necessary for the coil to complete a heating operation at one step as has been the usual practice in coil-type heaters. By initially heating the water in this manner, much of the lime deposit and other mineral solids are caused to settle out in the bottom of tank 51, and may be withdrawn through drain 71, whereby freeing the water of these mineral deposits before it enters the coil 63. Therefore, the coil 63 will be less likely to have these deposits accumulate therein and become clogged thereby, because much of such mineral matter would be removed by the preheating. Furthermore, the range of heating of the water on the coil is not as large as if the coil had to raise the temperature from the normal cold water temperature as introduced to the highest desired hot water temperature.

The coil 63 is removably supported within the flue 54 and the upper portion of combustion chamber 53 and it may be removed readily for cleaning or repair. This coil is provided with the customary unions at either end thereof and is carried by the brace 64 which supports said coil within the flue 54. With the coil 63 thus arranged, it acts as a baffle whereby a high heat recovery is possible from the spent flue gases which pass upward through the flue or vent 54 in contact with the coil, and thus the maximum heating efficiency is obtained.

When it is desired to remove the coil 63, the pipe 65 may be capped at its lower end, and the pipe may be capped also where the coil is disconnected, and the valve 70 opened. Then by raising the temperature setting of the thermostatic valve 73, the system may be used until such time as the coil has been repaired and replaced. With the system thus arranged, the hot water may then be withdrawn through the pipe 68, through open valve 70, and out through hot water supply pipe 56. The actuation of the rest of the system will not be impaired as it will continue to operate in the same manner as hereinbefore described, except the water will flow out of the tank directly through the pipe 68, instead of passing through the coil 63.

The pipe 66 is shown as provided with a T 75 through which water at a sterilizing temperature may be withdrawn as desired upon proper setting of the valve 73. In that event, water at normal temperature may be withdrawn through the pipes 68 and 56 upon opening the valve 70.

Due to the fact that the heater tank is operated at such low temperature, little or no insulation is required, as the temperature may be only slightly higher than normal room temperature, as desired.

After water has been withdrawn from the system the burner will continue to burn and the circulation will be through check valve 69 until the water in the tank reaches the temperature of predetermined setting of the valve.

The form of the invention shown in Fig. 3 has a tank 81 with a combustion chamber 82 in the lower portion thereof, where heat is applied by a burner (not shown) to the lower portion of the tank and to a coil 83. The tank has a water inlet pipe 84 at the bottom thereof, and a water outlet pipe 85 which extends from the top thereof to a hot water storage tank 86. A hot water supply line 87 is provided at the upper portion of the hot water tank 86 for supplying moderately hot water therefrom to the point of use.

A pipe 88 extends downwardly from the storage tank 86 and is connected also with the lower portion of tank 81 through a check valve 89 so as to form a circulation loop. The pipe 88 is connected also through a pipe 90 with one end of the coil 83 within the combustion chamber 82. An outlet 91 is provided at the upper end of coil 83 for supplying water of a higher temperature than is supplied by water outlet pipe 87. A bypass 92 is provided between the pipe 85 and the upper end of the coil 83 so that water may circulate from the coil into the tank 86.

A diverter valve 96, similar in construction to the form of valve shown in Fig. 5, is used to direct water from cold water supply pipe 97 first through a pipe 98 into a perforated tube in tank 86, similar to tube 14b shown in Fig. 6. Then the diverter valve 96 will direct the water into a pipe 99 which is connected with the pipe 84 at the bottom of the tank 81.

The fuel is supplied through a line 100 having a thermostatic valve 101 therein to a burner (not shown) disposed in the combustion chamber 82. The burner and diverter valve are similar in construction to the assembly shown in Fig. 5.

The form of the invention shown in Fig. 3 utilizes a diverter valve and a perforated discharge tube in the tank that directs cold water against a control thermostat similar to that shown in Fig. 6. However, this form is recommended for large requirements of hot water where two different temperatures of water are desired. A moderately hot water may be withdrawn through the hot water supply pipe 87, as for example, this water may be about 140 degrees F., which is sufficiently hot for all ordinary purposes. However, at times it may be desired to have water of a higher temperature and at sterilization temperature by the use of a single heat source with the single thermostatic valve 101 disposed within the storage tank 86.

The pipe 88 passes from the lower portion of the storage tank 86 and connects with the pipe 90 which in turn connects with the lower end of the coil 83, which extends upwardly through the vent flue 102. The coil 83 has sufficient heat exchange surface to heat the water therein to a temperature desirable for sterilization purposes. When the water is not used for sterilization, the water in the heating coil 83 will pass outward through the by-pass 92, through check valve 93, and through pipe 85 into the storage tank 86, thence down through pipe 88 and check valve 89 into the heater tank 81. However, a portion of the water will also circulate simultaneously through the coil 83 which will cause this accelerated thermo-syphon action.

By supplying the coil 83 from the pipe 90 at the 75

lowest point in the thermo-syphonic system, and discharging the water from the coil just above the heater in the flow line 85, instant rapid circulation is created between the storage tank 86 and the heater.

The form of the invention as shown in Fig. 4 comprises a tank 111 having a burner 112 disposed in a combustion chamber 113 in the lower portion thereof. The combustion chamber 113 has a flue 114 leading upwardly therefrom. A coil 115 is mounted in the upper portion of combustion chamber 113 and extends through the flue 114.

A cold water supply pipe 116 admits cold water into a diverter valve 117, shown in detail in Fig. 7. The valve 117 has a passage 118 connected with a pipe 119, and a passage 120 connected with a water inlet pipe 121 which extends to the lower portion of tank 111. The pipe 119 is connected with a storage tank 122 and has a perforated tube extending therein in close proximity to the thermostatic valve 123, similar to that shown in Fig. 6. A fuel supply line 124 is connected with the burner 112 through the thermostatic valve 123.

A pipe 125 interconnects the top of heater tank 111 with the storage tank 122, and a pipe 126 connects the lower portion of hot water storage tank 122 with the lower portion of the hot water tank 111 through a check valve 127. A pipe 128 connects the pipe 126 with the lower end of the coil 115. The upper end of the coil 115 has thermo-relief valve 129 disposed thereon, and has a by-pass 130 interconnected with the pipe 125, and a pipe 131 connected with the relief valve opening thereof for directing water to one end of a cylinder 132, as shown in Fig. 7. The cylinder 132 has a piston 133 disposed therein and mounted on an axial plunger shaft 134. A spring 135 is disposed in the cylinder 132 at the opposite side of the piston 133 from the inlet of the pipe 131. An orifice 136 extends through the piston 133 so as to connect a chamber 138 with a chamber 139 on opposite sides of the piston 133, forming a slow leak therebetween. A bleeder passage 139 is provided from the chamber 138 to drain fluid outwardly therefrom. The valve 117 is held in spaced relation from the cylinder 132 by spacers 140. The valve 117 has a packing gland 141 around the stem thereof where it passes through the end wall thereof. A single valve disc 142 having a double face thereon is mounted on the plunger rod 134. A seat is provided on either side of the disc so either outlet passage 118 or 120 may be closed, depending on the position of the valve 142.

The form of the invention shown in Fig. 4 is similar in operation to the other forms described above, except that the diverter valve 117 is operated by pressure and may be located at a remote point from the heater tank 111. In the operation of this form, the cold water enters through a pipe 116 to the storage tank 122 and a perforated tube similar to the form shown in Fig. 6, which will cause thermostatic valve 123 to open, causing burner 112 to be ignited by pilot light 112'. This will heat the water in the coil 115, causing the water to circulate through the coil and through the thermo-relief valve 129, into the by-pass 130, thence into the pipe 125.

The thermo-relief valve 129 will open a passage into the line 131 which will direct the water, under pressure, to cylinder 132, as shown in Fig. 7. The pressure therein will cause the piston

133 to move against the tension of the spring 135, moving the plunger rod 134 longitudinally, thereby causing the valve disc 142 to seat in the opposite direction and close the passage 118. This will divert the water from the water inlet 116 outward through the passage 120 into the pipe 121, thence into the bottom of the heater tank 111. The water then will be initially heated and pass outward through the pipe 125 into the storage tank 122 for withdrawal through hot water supply pipe 122'. However, a portion of the water will circulate back from the tank 122 through the pipe 126 either through the check valve 127 into the tank 111, or through pipe 128 into the coil 115 from which it will flow through the by-pass 130 into the pipe 125, so as to complete a circulation loop. In normal operation, the major portion of the water will be circulated through the coil 115.

When the water in the storage tank 122 reaches the temperature determined, according to the setting of the thermostat, the thermostatic valve 123 will close the fuel supply line 124 which will extinguish the burner 112. Therefore, with the coil 115 not being heated, the thermo-relief valve 129 will cool so as to close the passage 131 leading to the cylinder 132. With the passage 131 closed, the water within the chamber 137 will leak through the small orifice 136 in the piston 133. This will permit the spring 135 to urge the piston into the position shown in Fig. 7. The water will flow from the chamber 138 through the drain passage 139 into a waste drain. The orifice 136 will be relatively small compared to the pipe 131, whereby the amount of water wasted by the operation of the valve will be negligible.

The form of the invention shown in Fig. 4 will provide a rapid thermo-syphonic circulation through the pipe 126 and coil 115 into the pipe 125 and back into storage tank 122, so as to obviate the necessity of a mechanical pump for circulation.

This installation is particularly desirable for large requirements of hot water at one temperature. It provides the same rapid circulation described above.

While each of the forms has been described in detail, it is pointed out that a cold water inlet directing cold water to a point within the immediate region of the thermostat that controls the fuel supply to the burner or other heating element is common to all forms, and immediately upon turning on the burner all or the greater part of the cold water is directed into the heating tank.

By selecting the proper installation herein-described depending on the requirements and also depending on conditions of water in the locality of installation, a system of hot water is available for any and all requirements, at maximum efficiency possible, and at minimum cost of operation and maintenance.

In the forms shown in Figs. 2 and 3, two temperatures of water may be maintained for withdrawal, by the use of a single thermostatic fuel supply valve controlling a single heating unit or burner in the combustion chamber.

I claim:

1. In a water heating system, a tank adapted to contain water and having an outlet therefor, said tank having a plurality of cold water inlets, heating means for the water, a cold water supply, means for directing water from said cold water supply to one of said tank inlets, means for actuating the water heating means upon the

direction of cold water to said tank inlet, and means operated in response to the actuation of the heating means for directing water from the cold water supply to the other tank inlet at a point in close proximity to the source of heat.

2. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostatic control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, and means connecting said heater tank and said storage tank to permit the passage of heated liquid from said heater tank to said storage tank.

3. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostatic control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, and means connecting said heater tank and said storage tank to permit the passage of heated liquid from said heater tank to said storage tank, and means forming a return passage from said liquid storage tank to said heater tank independent of said connecting means to permit recirculation of liquids between said tanks.

4. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof, upon withdrawal of heated liquid from said storage tank, a fuel supply valve, a thermostatic element located within a cold liquid inlet region of said liquid storage tank for controlling the fuel supply valve, a fuel supply line connected through said thermostatic control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, said diverter valve comprising a thermostatic element adapted for switching said valve mecha-

nism so as to close certain of said passages and to open other of certain passages in response to change in temperature as applied thereto, and means for connecting said heater tank and said storage tank to permit the passage of heated liquid from said heater tank to said storage tank.

5. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostat control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, said diverter valve comprising a thermo-element adapted for switching said valve mechanism so as to close certain of said passages and to open other of certain passage in response to change in temperature as applied thereto, and means for connecting said heater tank and said storage tank to permit the passage of heated liquid from said heater tank to said storage tank, a liquid outlet pipe having one end connected with a portion of said liquid storage tank, a heat exchange member disposed within the area heated by the heating element and connected with the other end of said liquid outlet pipe, the other end of said heat exchange member connected with an outlet for supplying heated liquid at a higher temperature than maintained in said heated liquid storage tank.

6. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostat control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, said diverter valve comprising a thermo-element adapted for switching said valve mechanism so as to close certain of said passages and to open other of certain passages in response to change in temperature as applied thereto, and means for connecting said heater tank and said storage tank to permit the passage of heated liquid from said heater tank to said storage tank, a liquid outlet pipe having one end connected with a portion of said liquid storage tank, a heat exchange member disposed within the area heated by the heating element and connected with the other end of said liquid outlet pipe, the other end of said heat exchange

member connected with an outlet for supplying heated liquid at a higher temperature than maintained in said heated liquid storage tank, and a by-pass connection inter-connecting the discharge end of said heat exchange member with the connecting means leading to said liquid storage tank from the heated tank.

7. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostat control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, said diverter valve comprising a thermo-element adapted for switching said valve mechanism so as to close certain of said passages and to open other of certain passages in response to change in temperature as applied thereto, and means for connecting said heater tank and said storage tank to permit the passage of heated liquid from said heater tank to said storage tank, a liquid outlet pipe having one end connected with a portion of said liquid storage tank, a heat exchange member disposed within the area heated by the heating element and connected with the other end of said liquid outlet pipe, the other end of said heat exchange member connected with an outlet for supplying heated liquid at a higher temperature than maintained in said heated liquid storage tank, said heat exchange member comprising a pipe coil disposed within said heated area.

8. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostat control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, said diverter valve comprising a thermo-element adapted for switching said valve mechanism so as to close certain of said passages and to open other of certain passages in response to change in temperature as applied thereto, and means for connecting said heater tank and said storage tank to permit the passage of heated liquid from said heater tank to said storage tank, said diverter valve controlling means comprising a bimetallic unit disposed within the region of the

heating element, and control valve means connected with an end of said unit.

9. In a liquid heating system, a heating tank having an inlet and an outlet, a liquid storage tank having inlets and an outlet, a diverter valve having an inlet and a plurality of outlets, means for directing a cold liquid through an outlet in said diverter valve and into said liquid storage tank through one of the inlets thereof upon withdrawal of heated liquid from said storage tank, a fuel supply valve, a thermostatic element located within a cold liquid inlet region of said liquid storage tank for controlling the fuel supply valve, a fuel supply line connected through said thermostat control valve for supplying fuel, a heating element at the lower portion of said heating tank and connected with said fuel line, means responsive to combustion at the burner for controlling said diverter valve so as to close the first-mentioned outlet and open another outlet so as to direct cold liquid into said heater tank, and means connecting said heater tank and said storage tank to permit the passage of heated liquid from said heater tank to said storage tank, the cold liquid inlet of the storage tank having a tube connected with the cold liquid directing means and arranged in said storage tank with means for directing cold liquid therefrom into proximity with the thermostatic element to cause actuation thereof.

10. In a liquid heating system, a tank having two inlets and an outlet, a diverter valve having an inlet and two outlets, thermo-control means for actuating a diverter valve for directing cold liquid from the diverter valve to one of the tank inlets upon withdrawal of heated liquid therefrom, a thermostatic valve means arranged in the region of said cold liquid inlet and responsive to the admission of cold liquid thereto, a fuel supply line connected with said valve, a burner connected with said fuel supply line and arranged to heat the liquid supply to said tank and means responsive to the combustion in the burner for controlling an outlet of the diverter valve connected with a cold water inlet of the tank.

11. In a liquid heating system, a tank having two inlets and an outlet, a diverter valve having an inlet and two outlets, thermo-control means for actuating a diverter valve for directing cold liquid from the diverter valve to one of the tank inlets upon withdrawal of heated liquid therefrom, a thermostatic valve having thermostatic means arranged in the region of said cold liquid inlet and responsive to the admission of cold liquid thereto, a fuel supply line connected with said valve, a burner connected with said fuel supply line and arranged to heat the liquid supplied to said tank, and means responsive to the heat of combustion at the burner for directing liquid from the other outlet of the diverter valve into heat exchange relation with the burner to be heated thereby and for directing said heated liquid to the tank.

12. In a liquid heating system, a tank having two inlets and an outlet, a diverter valve having an inlet and two outlets, means for directing cold liquid from one of the outlets of the diverter valve to one of the tank inlets upon withdrawal of heated liquid therefrom, a thermostatic valve having thermostatic means arranged in the region of said cold liquid inlet and responsive to the admission of cold liquid thereto, a fuel supply line connected with said valve, and a burner connected with said fuel supply line and arranged

to heat the liquid supplied to said tank, and means for directing liquid from the other outlet of the diverter valve into heat exchange relation with the burner to be heated thereby and for directing said heated liquid to the tank, and means responsive to the heat at the burner for controlling the diverter valve to direct cold liquid to the first-mentioned inlet of the tank upon withdrawal of liquid therefrom and to direct liquid to the heating means for heating thereby during operation of the burner.

13. In a liquid heating system, a tank having two inlets and an outlet, a diverter valve having an inlet and two outlets, means for directing cold liquid from one of the outlets of the diverter valve to one of the tank inlets upon withdrawal of heated liquid therefrom, a thermostatic valve having thermostatic means arranged in the region of said cold liquid inlet and responsive to the admission of cold liquid thereto, a fuel supply line connected with said valve, and a burner connected with said fuel supply line and arranged to heat the liquid supplied to said tank, and means for directing liquid from the other outlet of the diverter valve into heat exchange relation with the burner to be heated thereby and for directing said heated liquid to the tank, and means responsive to the heat at the burner for controlling the diverter valve to direct cold liquid to the first-mentioned inlet of the tank upon withdrawal of liquid therefrom and to direct liquid to the heating means for heating thereby during operation of the burner, a secondary heat exchange member connected with the tank to withdraw liquid therefrom and to cause further heating of said withdrawn liquid, and an outlet connected directly with said secondary heat exchange member for discharge of the liquid therefrom.

14. In a water heating system, a tank adapted to contain water and having an outlet therefor, said tank having a plurality of inlets, heating means for the water, a cold water supply, conduit means connecting said cold water supply with said inlets, a valve in said conduit means for controlling the flow of cold water to said inlets, means for actuating said valve to direct water from said cold water supply to one of said inlets, means for actuating the water heating means upon the direction of water to one of said inlets, and means responsive to the actuation of said heating means for actuating said valve to direct water from said cold water supply to another of said inlets.

MARTIN A. THOMAS.
